PACKAGE FORMING MACHINE

Frederick E. Bickford, Rye, N. Y.

Application April 1, 1944, Serial No. 529,066

9 Claims. (Cl. 93—51)

1

The present invention relates to a packaging machine and particularly to a machine generally similar to that of Patent No. 2,147,632 of February 21, 1939, as modified by Patent No. 2,265,024, issued December 2, 1941. The machine as described in that patent formed a package from a sheet of cellulose acetate or other thin, flexible material of like character in the following manner.

A sheet of material, the width of which was equal to the width of the base plus twice the height of a package to be formed plus an amount for cover flaps, was taken from a reel and passed through a mechanism which caused longitudinal reinforcing strips to be adhered to the original sheet relatively near the margin thereof and specifically along the lines where the bases and sides were to join in the final packages, the longitudinal strip forming reinforcing for the sides of the packages. Following this, transverse reinforcing tray-like structures were caused to be adhered to the original sheet between and at right angles to the longitudinal reinforcing strips at spaced points corresponding to the length of a package. Thereafter, the tray-like structures were cut along their center lines and the underlying sheet cut at the same time, the sheet being also cut along the ends of the tray-like structures. Subsequently the half trays were rotated about their edges to form ends of the package trays and thereafter the longitudinally reinforced edges of the sheet were folded upwardly and caused to adhere to the corners formed by the reinforcing half trays. Following this the completed trays were filled, if desired, and then a cover sheet was fed from a drum above a steel tongue which extended over a number of packages. This tongue was held upwardly (against rollers) by magnetic means so that it formed a support against which the side flaps were folded downwardly and adhered to the edges of the cover sheet.

The present invention, as has been stated, contemplates a machine generally similar to that described above but different in some respects; one of these is that the present machine not only has means for placing and adhering reinforcing end trays to the base sheet but also provides a means for fabricating such trays from cellulose acetate, or other moldable sheet material. The trays formed from cellulose acetate by the means disclosed in this application may not only be used to form reinforcing ends for packages but in addition trays made on this mechanism may be used to form complete packages. This would be accomplished by utilizing two trays of slightly different dimensions, one as the base and the

2

second as the cover for a package. Moreover, the present machine differs from that of the patent above mentioned as well as from the machine discussed in my prior Patent No. 2,147,632 of February 21, 1939, as to the driving mechanism provided and also with respect to the means for assuring the application of vacuum to the link structure. Additionally, the machine of the present invention may be provided with a link structure having top plates in duplicate so that two packages may undergo the same formative steps at the same time.

It is an object of the invention to provide mechanism for forming trays and applying them to sheets of cellulose acetate or the like in such manner as to become the ends of a package.

It is another object of the invention to provide mechanism for applying the formed trays to a sheet of cellulose acetate or other flexible material.

20 It is a still further object of the invention to provide a mechanism in which trays may be made in such manner that two of these trays taken together may form a complete package.

It is a further object of the invention to provide means whereby two packages may undergo the same formative steps simultaneously on a single machine.

It is a still further object of the invention to provide an improved driving mechanism for the moving links of a chain type of packaging and package forming machine, whereby variation in the link spacing is provided for.

It is a still further object of the invention to provide an improved link structure comprising a new form of contact shoe for the vacuum tube and an improved connection therefrom to the top plate for such a machine which together assures that there be no loss of the suction applied to the moving links thereof.

40 Figure 1 is a fragmentary cross sectional view of a package forming and packaging machine showing means for forming and applying end trays to a sheet of cellulose acetate or the like and showing also the mode of applying vacuum to the moving links of the package forming machine on which a sheet of cellulose acetate to which the trays are applied is registered. This view likewise shows an improved mode of constructing the links of a moving chain to assure the application 45 of suction to the cellulose acetate with substantially no loss of suction during transmission. In this figure poppet valves are shown (with a helical cam shaft for actuation thereof) and it is evident they are required only when the links are 50 spaced apart and are not needed when shoes abut

end to end; since the pump capacity may be increased to care for the slightly increased leakage resulting therefrom.

Figure 2 is a side elevational view of the tray forming mechanism of Figure 1.

Figure 3 is a top plan view of the tray forming mechanism.

Figure 4 is a longitudinal cross section of one half of the mechanism of Figure 3 taken on the plane of the line 4-4 of Figure 2.

Figure 5 is a longitudinal cross section of one half of the mechanism of Figure 3 taken on the plane of the line 5-5 of Figure 2.

Figure 6 is a plan view of a strip of cellulose acetate or like moldable material from which the trays are formed. This view shows the strip after holes and slots have been punched therein and score lines have been made thereon to aid in the formation of the tray. As hereafter will appear these lines and punchings can be formed in the strip either in the present machine or in a separate machine as is preferable.

Figure 7 is a top plan view showing a section of the strip as it appears after the first operation performed thereon in the machine of this invention, that is to say after it has been perforated along center line and cut from the length of strip supplied to the machine.

Figure 8 shows the strip of Figure 7 after the sides and ends have been bent up and are in position to have the end flaps bent over and adhered to the side flaps.

Figure 8a is a side elevation of the strip of Figure 7 showing the appearance of the partially formed tray when seen from the side.

Figure 9 shows the end flaps bent over the sides and adhered thereto.

Figure 9a is a view similar to Figure 8a showing the tray and also illustrating the operation of part of the forming mechanism.

Figure 10 is a view generally similar to Figure 8 but showing a mode of forming flaps on the sides and adhering them to the ends of the tray rather than forming flaps on the ends and adhering them to the sides.

Figure 11 is a transverse cross sectional view of the machine of Figure 1 showing particularly the mode of driving the links of the chain and the construction of the links for eliminating any loss of vacuum or suction which might have been present in the construction shown in my earlier patents and particularly in Patent No. 2,130,761 of September 20, 1938; and

Figure 12 is a transverse cross sectional view of a link structure in which registration platforms are provided in duplicate so that two packages may proceed through the same steps in formation simultaneously. In this structure the tray applying mechanism is of course likewise provided in duplicate and is so illustrated in the drawing.

The sheet of material from which the bottom and sides of the package are to be formed is supplied with longitudinal reinforcing strips in the same manner as is shown in my Patent No. 2,147,632 the base sheet being creased or folded at the inner margin of the reinforcing strips as is shown in the patent mentioned.

Since many of the structural elements shown in the drawings are identical with those of my Patent No. 2,265,024 above mentioned, the reference characters used are those used to identify corresponding parts in the patent.

After the base sheet has been provided with the longitudinal reinforcing strips as above men-

tioned, it is fed to the links 10 of a moving chain on which the material is registered in proper position by the application of vacuum through the passages of the links. The links are then advanced to a position such as that shown in Figure 1 of the drawings in which each of three chain links lies beneath the mechanism for forming and applying reinforcing ends to the longitudinally reinforced strip.

With the links stationary (as they periodically are due to a suitable driving mechanism as for example a Geneva movement or the like) in the position specified reinforcing tray-like members generally designated 11 are applied transversely to the sheet between the first and second and the second and the third links. The mechanism for making and applying these tray-like reinforcing members is shown in Figures 1 through 5 and comprises two portions one of which is a mold and the other a plunger. The plunger mechanism serves not only to form the reinforcing trays but also to apply these trays when formed to the base sheet. This plunger member is identical with the similar member of the patent above mentioned but has the additional function of acting in cooperation with the mold to form the trays from a blank of cellulose acetate or other moldable sheet material.

Although, as has been stated, the plunger member is identical with that shown in my above mentioned patent, it will be described in some detail due to the fact that it serves the additional function of forming the trays. The plunger mechanism is shown particularly in Figures 1 and 2 of the drawings. It comprises a pair of yokes 12 between which a bar 13 extends. Each of the yokes has attached thereto an actuating rod 14, these rods extending upwardly and being guided at their upper ends in any suitable manner.

Spaced inwardly from the yokes 12 are supporting members 15 which serve as guideways for the tray lowering and folding members generally designated 16. Extending through these tray lowering and folding members 16 are slots 17 through which the bar 13 previously described passes. Fastened to members 16 are guiding members 18, see Figure 3, Patent No. 2,265,024) so that the slots 17 and guides 18 together guide the bars 13 for vertical reciprocation.

Each tray lowering and folding member 16 comprises a plate 20 having narrow flanges 21 at both sides thereof, these flanges extending in both directions and forming an H-shaped member in cross section. The ends of the flanges 21 of plate 20 terminate in points 22 which are sharpened and which serve to cut the base sheet at the proper time as will be later described. Likewise the bottom edge of plate 20 is formed with teeth 23 (see Figure 2) which are sharpened and which serve to cut the reinforcing trays 11 as well as the underlying base sheet as will also be later described.

Plate 20 is provided with slots 24 through the outer ones of which extend screws 24a which couple two tray inserting plates 25, these plates being also used in the present instance as a die member to cooperate with the mold in the formation of the trays. Fastened to the plate 20 are four flat springs 26 having curved lower ends, these springs being fixed to the plate 20 at their upper ends only and being located one on either side of each face of plate 20. The tray inserting plates 25 are grooved opposite the springs 26 so that the springs may slide within the grooves in

a manner which will be described hereafter. At the lower end of each groove each plate 25 is notched (as shown at 27, Figures 11 and 13 of Patent No. 2,265,024) for a purpose which will become apparent when the operation of the mechanism is described. Fastened to either face of plate 20 beneath the flat springs 26 is a rectangular piece of resilient material (28, Figures 11 and 13, Patent No. 2,265,024) each of which is bowed outwardly at its lower extremity. This rectangular sheet is provided with slots similar to the slots 24 so that the screws 24a holding the two plates 25 together extend likewise through these resilient pieces.

Fastened to each yoke 12 is a downwardly extending member 31 which at its lower end forms a support for a hinge 31a to which are attached the two halves 33 of a templet 34, each of these templets being relatively short in the direction of the chain of links 10. Fixed to the bar 13 at the center thereof is a downwardly extending bar 35 which supports a hinge 35a on which two halves 36 of the templet 37 are supported. Templet 37 is generally similar to the templets 34 but is of considerably greater longitudinal length since this templet is to be inserted within and completely occupy a package forming tray whereas the short templets merely occupy the ends of package forming trays.

Cooperating with the tray applying members which have been above described are the mold members, or tray forming members of the instant invention. In describing these members the reference characters used have no reference to Patent No. 2,265,024 and it is to be understood that this is the case.

Each mold member comprises a channellike member 40 having a slot 39 (Fig. 1) in the base thereof, this slot extending about two-thirds of the length of the channel and terminating at the points designated 41 (Figure 5). Beneath the channel member 40 is a base 42 which is generally rectangular in shape and which has a rectangular slot 42a near the center thereof. The upstanding arms of the channel are cut as indicated at 43 (Figures 4 and 5) to provide space for the forming plates 44 which plates are adjustably positioned by means of the screws 45 and adjusting nuts 46 of Figure 4. In addition, these plates are heated by means of the electrical heaters 47 the leads 48 to which extend through holes in the upstanding arms of the channel as shown in Figure 5. At each end of each of the side forming plates 44 the channel is slotted transversely and outwardly of the slots the channel is filled in as, for example, by a metallic block, or may be made solid forming a flat surface, the sides of which are spaced from the ends of the side forming plates 44, these flat surfaces forming mold ends. The base for the mold is removable and comprises a bar 50 having tongues 51 thereon which fit in grooves 52 in the base of the channel 40. This bar is also provided with an electrical heating unit designated 53 the lead to which extends through the bar to a heater terminal at point 54. The bar is moved into and out of its position by means of rack teeth 55 (Figure 2) which are formed on the lower surface of the bar and which cooperate with a gear wheel 56 which is suitably driven for operation in time with the operation of the plunger member and other portions of the machine.

Located above the removable bottom or bar 50 and slidably mounted in grooves in the forming members 44 is a similar bar 250 which bar serves as the bottom of a mold formed by the upper

portions of plates 44 during a preliminary forming operation of the cellulose acetate or other moldable material as will appear hereinafter. This bar 250 is provided with rack teeth 251 on its lower surface, which teeth cooperate with a gear such as 252 (Figure 11), the gear being suitably driven for timed operation with the plunger member and other portions of the machine.

At each end of the slot in the base 42 and lying immediately above the removable bottom or bar 50, there is located an end bending and holding piece 57 which piece has a beveled edge 58 (Figure 2) and is urged into its innermost position by means of the spring 60 stretched between the lug 61 on the piece 57 and lug 62 formed integrally with the channel 40. These springs are adjustable by means of the screws and nuts 63 and 64 as is clearly shown in the drawings. Adjacent each corner of the slot in the base 42 but above the bar 50 is a flap folding member 65 each of which is mounted on a shaft 66 and is oscillatable from the position shown (Figure 5) to that in which its long edge lies parallel to the long edge of the slot in the base 42. The shafts 66 extend downwardly through bushings of the base 42 and carry on their lower ends gear sectors 67 which mesh with pinions 68 which in turn are mounted on shafts 70 which shafts extend through the base and cover and carry pinions 71 on their upper ends.

The pinions 71 at the lower right hand and upper left hand portions of the mechanism, as shown in Figure 3, mesh with idler pinions 72 which in turn mesh with pinions 73. The pinions 71 of the mechanisms at the upper right hand and lower left hand corners of Figure 3 mesh directly with pinions 73. In every instance the pinions 73 mesh in turn with gear sectors 74 which are mounted on shafts 75 extending upwardly and bearing pins 76 near their upper ends, see particularly Figure 2. Actuating members 77 are guided on the upwardly extending ends of the shaft 75 and have in their surfaces helical slots 78 into which the pins 76 extend. Thus when the members 77 are depressed they actuate the train of gears comprising the sectors 74, pinions 73, 72, 71, 68 and gear sectors 67 to operate the flap folding member 65. As has been indicated the shafts on which the pinions 68, 72 and 73 are mounted are stud shafts which extend into and are supported by the cover member 80 about to be described.

Cover member 80 is a plate which extends over and is fastened to the upright arms of the channel member 40. This plate is recessed in its lower surface to provide a passageway through which a blank of cellulose acetate or other moldable material may be fed. The recess extends to the right, as seen in Figures 4 and 5 to the point 81 the termination of the recess acting as a stop for the strip or blank of tray material. Also the cover 80 has a rectangular slot therein which lies immediately above the rectangular slot in the base 42. Above the plate 80 and spaced therefrom is a second plate 82 which has a large generally rectangular slot 83 therein and which serves as a support for the upper ends of the various pinion shafts mentioned as well as to hold in position brackets 84 which support horizontal shafts 85 on which are mounted the guiding rollers 86 for the tray forming and lowering member 16.

The base of the channel 40 extends outwardly therefrom to the left, as shown in Figure 2, and

carries at its end a bracket 87 which forms a support for the shaft on which gear 56 rotates. This extension at the base of the channel also carries a pair of brackets 88 fixed to the extension by means of the screws 90, these brackets forming a support for the shaft 91 on which a feed roller 92 is mounted. The feed roller 92 cooperates with and lies directly below a primary feed and perforating roll 93 which is mounted upon a shaft 94 which may be supported in any suitable manner not shown. The entire mold structure comprising the channel 40 and the other cooperating parts hereinabove described, is suitably mounted in a fixed position, this mounting being omitted from the drawings for the sake of clarity. The feed rolls 92 and 93 are designed to feed a blank such as that shown in Figure 6, and perforate that blank as shown at 99 in Figure 7.

This blank comprises a strip of cellulose acetate 95 or other moldable material of a width equal to the width plus twice the height of the tray to be formed and having certain perforations, scored lines and slots as shown in Figure 6 and about to be described. At intervals corresponding to the length of the tray to be formed, and consequently corresponding to the width of the ultimate package, holes 96 are punched on the longitudinal center line of the strip 95; these holes, as a result, being spaced apart a distance equal to the length plus twice the height of the trays to be formed. Running longitudinally of the strip and spaced inwardly from the margins thereof a distance equal to the height of the tray to be formed (and therefore equal to the height of the package to be formed) are score lines 97 which facilitate the turning up of the sides of the trays. On these score lines there are punched holes 98 which locate the corners of the bottom of the tray in such manner that the center point 96 of the bottom area is equidistant from the holes 98. Running transversely of the blank between the score lines 97, or between pairs of holes 98, are additional score lines 100 which facilitate the folding of the ends of the material as will be described later. Narrow slots are punched which extend from each one of the holes 98 outwardly to the margin of the strip, these slots serving to eliminate excess material and to absorb expansion. The feed roller 93 has ridges 93a thereon corresponding to the score lines 97 and 100. Likewise this roller has pins 101 thereon which cooperate with the holes 96 to cause feeding of the material a definite amount upon each half rotation of the feed roller. In addition to the ridges and pins mentioned, the feed roller 93 carries on its surface a plurality of teeth 102 which perforate the blank along its center line to facilitate the ultimate severing of the material subsequent to the application of the reinforcing tray to the base sheet.

In timed relationship to the operation of the main machine the feed roller 93 is operated to advance the strip of material into position such that its forward end (right hand as seen in Figure 2) comes against the end 81 of the recess in the cover 80. At this time the mold bottom or bar 50 is in its right hand position as seen in Figure 2, the upper bar 250 is in its left hand position as seen in Figure 2, and, of course, the end forming pieces 51 are in their inward positions to which they are urged by the spring 60.

Next the blank is severed from the strip by means of a knife 103 which descends through slots 109 (Figure 2) in the members 82 and 88, 75

the severed blank being shown in Figure 7. Following this the tray lowering member 16 with points 22 above the lower edges of plates 25, is caused to move downwardly until it rests against the bar 250. This action causes bending of the side and end portions of the blank upwardly as shown in Figure 8. Due to the seating of the lower edges of plates 25 against the bar 250 the action just above described results in forming accurate square cornered bends along the juncture of the bottom and sides of the tray. This result may, if desirable, be further assured by providing a heating element in the bar 250 in a manner similar to that in which bar 50 is provided with a heating element 53.

Following this action the bar 250 is moved to the right and the tray lowering member 16 is caused to move downwardly till it rests against the bar 50.

The extreme ends of the end portions extend beyond the side portions at this time and are permitted to descend in this form due to the cut-away portions of the sides of the channel 40 as is best illustrated in Figure 4 in which the slots formed by virtue of the construction are shown at 104. It will be seen that the beveled edges 58 of the members 51 presses against the material and hold the ends against the ends of the tray forming and inserting plates 25, which constitute a mold plunger. At this time flanges 21 lie above the edge of the tray end; this pressure of piece 51 against the tray ends assures that the flanges and cutting edges will pass outside the tray ends in their later descent. The presence of the semi-circular cuts resulting from severing the blank across the center lines of holes 96, assists the cutting of the tray. To increase this effect the holes may be made in a diamond shape, the feed pins being modified accordingly.

Following the operation above described the actuators 77 are moved downwardly causing rotation of the shafts 75 and consequent rotation of the flap folding members 65 which members act against the extended flaps on the ends of the blank to fold them against the upstanding sides 65 of the blank, the position of the folding members 65 after this operation being shown in Figures 9 and 9a. Since the heating elements have been energized at all times the pressure exerted by the members 65 upon the flaps of the ends of the blank causes these flaps to adhere to the sides of the blank and to complete the formation of a tray. If desirable adhesive may be substituted for heat.

Next the gear 56 is actuated to retract the mold bottom or bar 50 and the now formed tray carried by the tray applying member 16 is caused to descend through the rectangular slot in the base 42 and be applied to the longitudinally reinforced base sheet on the links 10. Means not shown are provided for spraying adhesive against the bottom of the formed tray as it descends into position on the base sheet or in the alternative the links may be provided at their ends with heating elements in order to cause adherence of the trays to the base sheets by means of heat and pressure. Shortly thereafter the plates 20 are lowered under control of their actuators the sharpened edges 21 and 23 thereof cutting through the centers of the bottoms and ends of the tray-like members 11 and perpendicularly to these cuts through the base sheet. In other words, the trays 11 are cut in half and the sheet is incised in an H-shape.

Following this the various parts of the members 16 are actuated in the manner described in

detail in my Patent No. 2,265,024 and specifically extending from line 59, column 1, page 4, to line 22, column 2 of that page. At this time the templets are still within the partially formed package trays and the half trays have been rotated into position to form package ends. Thereupon adhesive material or solvent for the base sheet and the trays 11 is sprayed between the longitudinal reinforcing strip and the corners of the members 11 and immediately thereafter the hinged sides 105 of the links 10 are rotated about their hinged points by means of the actuators 106 causing the reinforced edges or sides of the package to be adhered to the corner pieces formed from the trays 11.

It will be obvious that the material on the center link of the three is formed into a complete tray while that on each of the two outside links is formed into a single ended tray. However, the next movement of the links will be such as to advance them through two link lengths so that the tray having its forward edge previously formed will be in position to have its rear end formed thereby resulting in the effective completion of two complete trays on each operation. It will also be clear that in order to effect such a result the mold members comprising the channel 40 and its associated parts together with the tray forming and applying members 16 are supplied in duplicate, as is shown in Figure 1. It will moreover be clear that by the addition of a third molding member comprising the channel 40 and its associated parts and a third member 16, as is indicated by the dash-dot lines in Figure 3, three or more trays may be made simultaneously and applied to the base sheet to form effectively a corresponding number of complete package trays at each operation of the machine. If this is done it will, of course, be necessary to modify the drive of the links 10 so that on each intermittent actuation of the chain a movement of three or more link lengths occurs. Following the folding of the side members, as has been described, the package trays may be filled and covered, the side flaps being sealed to the covers in the same manner and with use of the same equipment described in detail in Patent No. 2,265,024 which equipment is shown in a rather schematic way to the right of the break in Figure 1.

It may at times, as has been above indicated, be desirable to utilize the tray forming or molding equipment described, for the purpose of forming a tray of proper size to be used as the base of a package and to use the same or a similar mechanism to form a slightly larger tray which will fit over the base tray to form a cover for such a package. When this is done the feed roller 93 will not be provided with teeth 102 since it is not desired to perforate the tray along its center line as is desirable when the tray is merely to be used for reinforcement for the ends and corners of a package forming tray as heretofore described. Furthermore, in utilizing the equipment for this purpose a solid plunger will be provided in place of the plunger which has been generally designated as 16. Also it may be preferable that flaps be formed on the sides of the tray rather than on the ends and that these flaps be folded over the ends rather than over the sides. To accomplish this the folding member 65 of Figures 8 and 9 are actuated in the reverse direction and, of course, the blank is modified in corresponding manner whereby the flaps, or in some instances, opening tab extensions of reinforcing strips embedded in the

material, are formed on the sides of the blank and are caused to be folded over the upstanding ends as is indicated in Figure 10.

Although, as has been stated, the machine is generally similar to that shown in my prior patents as modified particularly in Patent No. 2,265,024, improvements have been made in various portions of the mechanism. One of these improvements is concerned with the driving mechanism. In my earlier patents, the links of the moving chain were driven by means of sprocket wheels at either end of the machine augmented in some instances by a rotating rod bearing a helical groove and cooperating with projections extending outwardly and downwardly from the sides of the link and lying under the helical rods.

In the present instance the machine is positively driven by virtue of rack teeth 111 (Figure 20) cut into the lower surface of the downward extensions 110 at each side of each link. These rack teeth mesh with pinions 112, Figures 1 and 11, which pinions are mounted on the shafts 113 which extend transversely of the machine as is seen particularly in Figure 11. Alternate ones of the shafts 113 carry beveled gears 114 at their left ends and the remainder carry like beveled gears 114 at their right hand ends. In either event the beveled gears 114 mesh with beveled gears 115 mounted on the shaft 116 or 117 as the case may be. Shafts 116 and 117 extend longitudinally of the machine and each carries at one end thereof a spur gear 118 or 119 in turn meshing with the gears 120 or 121. These latter gears are driven in any suitable manner as, for example, that shown in Figure 21 of my Patent No. 2,130,761 issued September 20, 1938, which drive mechanism incorporates a Geneva movement such as has been mentioned.

40 In this construction the helically cut rods of my prior patents, such as those shown in Figures 1 and 2 of the patent above identified, are eliminated and in their place there is provided a rod 122 which bears against the upper surface of the lower portion of the extension 110 and causes the links to seat properly upon the vacuum supply tube. The rods 122 are tapered at one end so that as the links of the moving chain pass about freely rotatable wheels (not shown) at the ends of the machine, the lower portions of extensions 110 of the links are sure to pass under the rods and are then caused to be pressed into proper position on the vacuum tube 170 due to the tapered formation of the rod ends. The wheels at the ends of the machine 45 replace the sprocket wheels of Figure 21 of Patent No. 2,130,761, these wheels being plane surfaced and being rotatably mounted on the shaft so that the drive is through the rack teeth only.

50 In order that the length of the unit packages may be altered means are provided for separating the links of the moving chain as will be described hereinafter. In addition to this means it is, of course, necessary to provide a different size of top plate 123 and in addition, of course, it will be necessary to change the spacing of the tray making and applying members so that the reinforcing trays will be applied to the package ends.

55 The means for separating the links are shown in Figures 1 and 11 and comprise a downwardly extending portion of the link structure designated as 124 in the drawing, this portion having the rack teeth 111 cut in its lower surface

which extends to the right, as shown in Figure 1, and square teeth 111a in the upper surface of its extending portion. Furthermore, as will be most clearly seen in Figure 1, the downwardly extending portion of lug 124 is supplied in duplicate one on either side of the bottom portion of the L-shaped extension 110 of the link. Further each side of the bottom edge of the extension 110 carries square teeth as is indicated at 126 with the resulting effect, on either side of the lower edge of the extension of the link, of a slot cut into the link extension and provided with square cut teeth on either edge thereof. Through the portions 124 of each link extension a pivot screw 130 passes and on this screw is pivoted a connecting bar 127 which extends to the left of the pivot screw 130 as seen in Figure 1, and carries on its lower surface rack teeth 128 of the same conformation as the rack teeth 111.

As is clearly seen in Figure 11, this bar is of such a width as to lie between the two extensions of the portions 124. In order that the distance between the pivot screws may be varied two plates 131 are provided, these plates having square cut teeth on their upper and lower edges and being fastened to the bar 127 by means of the screws 132. When in position the square cut teeth on the edges of the two plates 131 (one lying in front of and one behind the bar 127) are engaged with teeth 126 on the upper edges of the slots in the link and with the square cut teeth along the upper edge of the projections 125 forming the slots.

Thus in order to adjust the distance between links, it is only necessary to remove the screws 132 and the plates 131 after which the bars 127 can be given a desired position with respect to the adjacent links and the plates reinserted with their teeth meshing with different ones of the teeth of the link structure after which the screws 132 may be reinserted and tightened.

In Figures 1 and 11 are also shown modifications of the link structure as compared with that shown in my prior Patents Nos. 2,147,632 and 2,130,761, these modifications being particularly with respect to the mode of transmitting the applied suction or vacuum through the body of the links to the sheet registering plates such as 140 of Figures 1 and 11. In the present instance each link comprises a generally rectangular body portion 141 carrying along its side edges the downwardly extending members 110 previously described. Body portion 141 has a round hole therein extending upwardly from its bottom edge almost to the top thereof of which hole is bushed with a bushing 142. Within this bushing is an upwardly projecting cylindrical member 143 which has a lower concave surface formed integrally therewith to which is fastened a shoe 144 which engages the vacuum or suction applying tube 170, there being a gasket 145 between the member 143 and the shoe 144.

Fastened to the shoe 144 at each end thereof are the upwardly extending U-shaped members or brackets 146 through which curved bars 147 attached to the downward extension 110 of the body portion 141 are fixed. This construction prevents the shoes and projections 143 from falling out of the link structure when that structure passes beyond the tube. A coil spring 148 is placed between each bushing 142 and a rim 150 formed on the cylindrical projection 143, the springs tending to hold the shoes against the vacuum tube during the traverse of the links along that tube and also forcing the upper surface

of the lower portion of extension 110 tightly against rod 122, thereby maintaining exact registration throughout contacts of shoes with tube.

In the same way was shown particularly in Figure 13 of my Patent No. 2,130,761, the rotation of a helically ribbed tube causes the operation of poppet valves to admit suction into the link structure at the proper time. In my prior patents there was no assured mode of transmitting this suction to the suction plates such as 140, the possibility of leaks occurring at the points between the various gaskets being relatively great.

In order to eliminate this defect the present structure provides an upwardly extending cylindrical boss 151 on the member 143, this boss being threaded on its external surface to cooperate with a nut 152. A reinforced flexible tube 155 such as a rubber tube reinforced with a coil spring is provided the rubber or other resilient portion thereof being flanged outwardly at its bottom end and seated upon the upper edge of the boss 151 being held in position by the inwardly extending flange of the nut 152. This tube extends upwardly and passes through a central hole in the bottom wall 25 of the registering plate structure 140 which bottom wall is likewise provided with an integral boss 153. A nut 154 similar to the nut 152 is provided and the flexible tube 155 is inserted through the boss 153 and bent over the upper 30 surface of that boss whereupon the nut is threaded on to the exterior threads of the boss clamping the flange of the tube between the inwardly extending flange of the nut and top of the boss. Of course, the sheet registering plate 35 123 of the upper link plate structure 140 is then fastened into its position, as shown in Figures 1 and 11.

It will be seen that due to the arrangement just described there can be no possible leak of the applied suction at any point during its transmission and particularly no leakage due to misregistration or due to wear, drying out or other gasket defects such as were possible in the structure of my earlier patents hereinabove mentioned.

It is at times desirable to increase the productive capacity of a machine of the type which has been described above. For this purpose a structure such as that of Figure 12 may be utilized. This structure is in general similar to that already described except that each link of the moving chain is in this instance provided with an upper plate 160 which distributes the vacuum from the tube 155 to two vacuum sheet registering plates 140 each carried at one side of the plate 160, the vacuum channels being shown at the right and left of the plate 160, and designated 161. This in effect supplies two chains of links each of which is cooperated with by tray forming and applying mechanisms identical with those previously described except that the feed of the blanks is in one instance from the left hand side and in the other from the right as will be obvious by reference to Figure 12. It will be understood, of course, that additional mechanism for filling the trays when formed and for applying cover sheets and for sealing the packages will also be provided being unnecessary to show this since they are simply duplicates of those indicated in Figure 1 and described in detail in my Patent No. 2,265,024 mentioned many times hereinabove.

In place of the duplicate top plates a single top plate of increased size may be utilized so that the resulting packages have greater transverse width than longitudinal length thereby causing the reinforcing and opening strips to run along

the ends instead of sides of the containers and likewise causing the opening tabs (flaps) to be folded against the sides instead of the ends by members 65.

What is claimed is:

1. In a device for making package trays, in combination, a mold member having a removable bottom element, upstanding sides extending above said bottom elements, upstanding end elements extending across said side elements at the upper portions thereof and being slightly spaced therefrom, additional end elements extending upwardly from said bottom member and being resiliently pressed inwardly, means for feeding a preformed blank above the molding chamber formed by the said bottom, side and end elements, a plunger of a size to substantially fill the said molding chamber and means for lowering said plunger against the blank to fold the sides and ends of the blanks upwardly to pass the extremities of the ends of the blank through the spaces between the upstanding mold sides and ends and to cause said ends to be pressed inwardly against the plunger by said resiliently pressed auxiliary end elements, the lowering of said plunger also serving to seat the base of said blank against said bottom element.

2. In a device for making package trays, in combination, a mold member having a removable bottom element, upstanding sides extending above said bottom elements, means for adjusting said sides toward and away from each other, upstanding end elements extending across said side elements at the upper portions thereof and being slightly spaced therefrom, additional end elements extending upwardly from said bottom member and being resiliently pressed inwardly, means for feeding a preformed blank above the molding chamber formed by the said bottom, side and end elements, a plunger of a size to substantially fill the said molding chamber, said adjustable sides, resiliently urged ends and plunger together rendering the mold chamber slightly variable in size, and means for lowering said plunger against the blank to fold the sides and ends of the blanks upwardly to pass the extremities of the ends of the blank through the spaces between the upstanding mold sides and ends and to cause said ends to be pressed inwardly against the plunger by said resiliently pressed auxiliary end elements, the lowering of said plunger also serving to seat the base of said blank against said bottom element.

3. In a device for making package trays, in combination, a mold member having a removable bottom element, upstanding side members extending above said bottom element, upstanding end members extending across said side members and slightly spaced therefrom, means for feeding a preformed blank above the molding chamber formed by the said bottom member and side and end members, a plunger of a size to substantially fill the said molding chamber, means for lowering said plunger against the blank to fold the side and ends of the blank upwardly to pass the extremities of the ends of the blank through the space between the said mold sides and ends and to seat the base of said blank against said bottom member, means located adjacent the corners of the molding chamber to bend flaps on the ends of the blank against the sides, means for heating the upstanding members and bottom element to cause adhesion of the bent flaps to the sides and means for removing said removable bottom element and further lowering

said plunger to remove the formed tray from the device.

4. In a device for making package trays, in combination, a mold member having a removable bottom element, upstanding sides extending above said bottom element, upstanding end members extending across said side members and slightly spaced therefrom, an auxiliary bottom element extending between said side members adjacent the top thereof, means for feeding a preformed blank above the molding chamber formed by the said bottom elements and side and end members, a plunger of a size to substantially fill the said molding chamber, means for lowering said plunger against the blank to fold the sides and ends of the blank upwardly and to seat the base of said blank against said auxiliary molding element, the extremities of said ends lying in the said spaces between said mold sides and ends, means for removing the auxiliary molding element and further lowering said plunger to complete the bending into place of the sides and ends of the box blank, and to pass the extremities of the ends through the said spaces, means located adjacent the corners of the molding chamber to bend flaps on the ends of the blank against the sides, means for heating the upstanding members and bottom element to cause adhesion of the bent flaps to the sides, and means for removing said removable bottom element and further lowering said plunger to remove the formed tray from the device.

5. In a device for forming reinforcing tray like members and applying said members to a sheet of cellulose acetate or the like, in combination, a molding chamber comprising a removable bottom element and upstanding side and end elements, said end elements being spaced from the ends of said side elements, a plunger adapted to be lowered into said molding chamber, means for feeding preformed blanks into position above said molding chamber, means for lowering said plunger against said blank to force the blank into the chamber and to cause bending of the sides and ends of said blank upwardly, and to pass the extremities of the ends of the blank through the spaces between said mold sides and ends, means located adjacent the corners of said chamber to fold the flaps of the ends of the blank against the sides thereof to form a tray, means to remove said removable bottom element, means to lower said plunger and to carry the formed tray from the molding chamber into contact with a sheet of cellulose acetate or the like in position beneath said tray, means to cause said tray to adhere to said sheet, and means carried by said plunger to cut said tray in half and to make an H-shaped incision in said sheet whereby the two half trays may be rotated about their edges to form reinforced ends for the ultimate package.

6. In a device for forming tray like reinforcing members to be used as end reinforcements for a package formed from sheets of cellulose acetate or the like, in combination, a molding chamber comprising a bottom and upstanding end and side walls, said end walls being spaced from the ends of said side walls, means for sliding said bottom to open the mold, means for heating said bottom, means for heating said side walls, means comprising a plunger located above said molding chamber for inserting a box blank into said mold, the sides of said box blank being bent upwardly due to cooperation of said side walls with said plunger, the ends of said blank being likewise bent upwardly due to cooperation of the end walls

with said plunger, said ends extending outwardly beyond the bent up sides, means comprising pivotally mounted arms located adjacent the corners of the mold for bending the extending ends against the bent up sides and adhering the ends to said sides due to the heat of the side walls and the pressure imparted by said bending means, means located adjacent the ends of the molding chamber spring pressed inwardly to hold the ends in position against the plunger during said bending of the extensions of said ends against the sides and means operable at the completion of the bending operation for removing said bottom element and ejecting the formed tray like member from the molding chamber due to additional movement of the said plunger.

7. A mold for use in the formation of package trays comprising upstanding side members, a removable solid bottom, fixed end members extending across at least the upper portions 20 of said side members and being slightly spaced therefrom, and means pivotally mounted beneath said end members for folding the end flaps formed in the space between said side and end members against the sides of a formed tray.

8. A mold for use in the formation of package trays comprising upstanding side members, a bottom member, end members extending across said side members and being slightly spaced therefrom, and an auxiliary bottom member mounted 30 for movement into and out of position above said first mentioned removable bottom member.

9. A mold for use in the formation of package trays comprising upstanding side members, a removable bottom member, end members ex- 35

tending across at least the upper portions of said side members and being slightly spaced therefrom, an auxiliary bottom member mounted for movement into and out of position above said first mentioned removable bottom member, said auxiliary bottom member cooperating with said side and end members to form a tray having end flaps extending into the spaces between said side and end members, and means pivotally mounted beneath said end members for folding said end flaps against the sides of a formed tray, said folding members operating subsequent to the removal of said auxiliary bottom member.
